UNITED STATES PATENT OFFICE

LEO ROSEMAN, OF NEWARK, NEW JERSEY

HOOK-FASTENER TAPE AND METHOD OF APPLYING SAME TO GARMENTS

Application filed July 10, 1926. Serial No. 121,527.

This invention relates, generally, to hook fastener tape and to a method of applying the same to garments.

This invention has for its principal object 5 to provide a novel tape having hook-fasteners connected therewith in desired spaced apart relation; and the invention has for a further object to provide a novel method of applying such hook tape to a marginal 10 edge portion of a garment opening, in such manner that the bodies of the hooks are covered and concealed with only the bills of the hooks exposed along the garment opening edge; the arrangement being such that a neat 15 and less bulky construction of hook supplied meeting edge portion for garment openings is furnished.

Other objects of the present invention, not at this time more particularly enumerated, 20 will be clearly understood from the following detailed description of the same.

The invention is clearly illustrated in the accompanying drawings, in which:—

Figure 1 is a front face view of a tape having secured thereto in accordance with the principles of this invention suitably spaced apart hook fasteners; Figure 2 is a rear face view of the same; and Figure 3 is a cross section through the tape, taken on line 3—3 in 30 Figure 2, the same being drawn on an enlarged scale.

Figures 4 and 5 are respectively rear face views of the novel hook fastener provided tape, showing modified arrangements of fastening stitching for securing the hook fasteners thereto.

Figure 6 is a plan view illustrating the first 40 step or stage in applying the novel hook fastener tape to the meeting edge portion of a garment opening; Figure 7 is a cross sectional view, taken on line 7—7 in said Figure 6; Figure 8 is a plan view illustrating the finishing step or stage in applying the novel hook fastener tape to the meeting edge portion 45 of a garment opening; and Figure 9 is

a cross sectional view, taken on line 9—9 in said Figure 8.

Similar characters of reference are employed in all of the hereinabove described views, to indicate corresponding parts.

Referring first to Figures 1 to 3 inclusive of the drawings, the reference character 10 indicates a tape of suitable width. This tape may be formed from any suitable fabric or textile material either in single ply or in two-ply form as may be desired. The hook fasteners may be of any desired form providing base wings or members 11 from which extends the shank portion 12 which terminates in the turned-over hook-bill portion 13. Said hook fasteners are disposed in desired longitudinally spaced apart relation upon the tape 10, with the base wings or members 11 thereof superimposed on the rear side thereof, and with the shank portions 12 directed toward and across an edge 14 of said tape so that the hook bill portions 13 extend around such edge 14 to overlie the outer face of the tape. When the hook fasteners are thus related to the tape, the same are initially secured thereto by a line 70 of stitching 15 extending across the base wings or members 11 thereof, said line of stitching including at each hook fastener location groups of laterally extending tying stitches 16 and 17 which are respectively sewn across the rear ends of the respective base wings or members 11 of each hook fastener, said groups of tying stitches 16 and 17 being connected by jump stitching 18. It will be clearly evident that 75 the detail arrangement and relation of the stitching 15 by which the hook-fasteners are initially secured to the tape may be variously modified, and need not be limited necessarily to the arrangement and relation just described above. For example, the line of stitching 15 may be so disposed as to permit of the extension of the tying stitches 16 and 17 across the forward ends of said base wings or members 11 of the hook-fasteners with the 80

85

90

jump stitching 18 extending over the shanks 12 of the latter (as shown in Figure 4); or (as shown in Figure 5), two lines of stitching 15 may be provided, with the tying stitches 16 and 17 extending across both the rear ends and forward ends of the hook-fastener base wings, and with the jump stitching 18 either running across a portion of the hook-fastener body, as shown in Figures 4 and 5, or exteriorly of such body, as shown in Figures 1 and 2; or any other relation of tying stitches and jump stitching relative to the hook-fastener body, which may be deemed desirable, may be employed within the scope of the present invention.

The hook-fastener provided tape, constructed and arranged as above described, is relatively inexpensive and is reduced to a minimum of thickness or bulk; it therefore provides, per se, a novel economical product of its kind, in which the hook-fasteners are initially disposed in desired predetermined spaced relation one to another ready for application to a garment at one opening edge thereof, and so as to accurately cooperate with eye fastening means applied to the opposite opening edge of said garment in any suitable manner familiar to those skilled in the garment manufacturing industry.

The novel construction of hook-fastener tape above described is adapted for application to the garment to be served thereby in and by a novel method of application, which is also a subject of this invention, and which will now be described.

Referring to Figures 6 to 9 inclusive, the reference character 19 indicates a garment body having a marginal edge portion 20 to which the hook fastener tape is to be operatively related. In applying the tape 10 to the garment 19, the latter is disposed with its outer face upward, and the tape 10, with its edge 14 inward, is laid upon and registered with the marginal edge portion 20 of the garment, and with its rear face downward, thus disposing the bodies of the hook fasteners between the garment material and the tape body, with the hook bills 13 initially exposed in inward projection (all as shown in Figures 6 and 7). When the tape 10 is thus related to the garment, a line of fastening stitches 21 is sewn through the garment and the tape 10 adjacent to the edge 14 of the latter, thus initially securing said tape to the garment. Said line of stitches 21 may include, at each side of each hook shank 12, a group of tacking or reenforcing stitches 22. Said tacking or reenforcing stitches 22 not only reinforce the secured relation of the tape to the garment at the points of exterior projection of the hook shanks, but also serve to bound the sides of the latter so as to prevent undue lateral play or other displacement of the same. It will be obvious that the described secured together relation

of the tape and garment will serve to completely enclose and conceal the hook fasteners, excepting their exteriorly projecting bill portions, without necessity for employing extra covering strips in connection with the tape. 70

After the tape has been initially secured to the outer face of the garment in the manner above described, the marginal portion 20 of the garment, with which the tape is coincident, is turned downwardly and doubled under and back upon itself, in the direction of the arrow shown in Figure 7, thus positioning the tape along the inner or rear side of the garment body along an opening edge thereof, while at the same time turning such garment edge to produce a hem-like smooth finished edge portion of neat and trim appearance. When the tape is thus positioned, the edge 14 thereof is outwardly presented in alignment with the margin of the garment opening, while at the same time the hook bills 13 are operatively disposed in proper exteriorly projecting relation to the margin of said garment opening (all as shown in Figures 8 and 9). To complete the operative attached relation of the tape 10 to the garment a second line of fastening stitches 23 is sewn through the folds of the garment and through the remaining edge portion of the tape, as shown in Figures 8 and 9. 85

The structure resulting from the use of the above described novel form of hook-fastener tape and from the aforesaid novel method of applying the same to the garment, not only produces a very neat and strong attachment of properly spaced hook-fasteners to the desired meeting edge portion of a garment, but also reduces the bulk and thickness of the fastener provided area of the garment to a minimum, while nevertheless adequately concealing the bodies of the hook fasteners per se, as is desirable. 100

It will be obvious that considerable variation in the form and arrangement of the tape attaching stitching 21, 22 and 23 is possible, and consequently I do not limit myself especially to the forms of such stitching shown in the drawings and above described, which are shown and described by way of example, and merely as a preferable form thereof. 105

Having thus described my present invention, I claim:— 110

A method of attaching hook fasteners to garments, consisting in providing a tape having hook fasteners secured to the under side thereof with their bills disposed around one edge of said tape and over its outer face; then applying such tape to the outer face of the garment edge portion, with the edge of said tape with which said hook bills are coincident inward; initially securing said tape by stitching along said inward marginal 125 130

edge portion thereof, at the same time forming reenforcing tack stitches at each side of the hook bill of each hook fastener; then folding under the marginal edge portion of said garment to dispose the attached tape on the rear face of said garment; and finally stitching the free edge of said tape to the garment body.

5 In testimony, that I claim the invention
10 set forth above I have hereunto set my hand
this 8th day of July, 1925.

LEO ROSEMAN.
